UNITED STATES PATENT OFFICE.

CORALIE SELBY OLNEY, OF OAKLAND, CALIFORNIA.

ORNAMENTAL COVER FOR DESIGNATING THE CONTENTS OF SEALED CONTAINERS.

Application filed January 16, 1922. Serial No. 529,530.

To all whom it may concern:

Be it known that I, CORALIE S. OLNEY, a citizen of the United States, residing at Oakland, in the county of Alameda and State of California, have invented certain new and useful Improvements in Ornamental Covers for Designating the Contents of Sealed Containers, of which the following is a specification.

10 The hereinafter described invention comprises a cover adapted for the sealing of glass or other containers designed for the storage therein of fruits and jellies, the same being of such design and construction as to 15 enable the housewife or others determining at a glance the nature of the article sealed within the container; the objects of the invention being the production of a simple, neat, attractive, comparatively inexpensive, 20 durable and efficient closure or sealing cover having associated therewith a figured ornamentation or character which as to configuration, outline and color conforms to that of the product sealed within the container, thereby enabling the expensive and 25 highly attractive labels at present utilized to designate the contents of the container to be dispensed with.

To comprehend the invention, reference 30 should be had to the accompanying sheet of drawings, wherein:—

Figure 1 is a front elevation of a glass container or jar with the sealing or closure cover applied thereto, said cover having associated therewith a figure or character representative of a strawberry.

Figure 2 is a view of the cover detached from the container and having associated therewith a figure or character representative of a blackberry.

Figure 3 is a view similar to Figure 2 of the drawings disclosing a figure or character representative of a different fruit.

In the drawings, the numeral 1 is used 45 to designate an ordinary type of jar or container for preserved fruits and jellies, provided with the usual outstanding circumferential flange 2. The closure or sealing cover 3 preferably formed of metal is provided 50 with a depending flange 4 for engagement with the flange 2 of the jar or container 1. The flange 4 of the cover may be secured to the flange or neck 2 of the jar or container in any suitable manner, such for instance as 55 employed with the cover of an ordinary Mason fruit jar commonly used by house-

wives for the putting up of preserves, fruits and jellies.

In the present case, the cover 3 is provided with a base 5 in relief, from which springs 60 or upstands an ornamental figure or character 6 having the shape, configuration, outline and color of the fruit or jelly contents of the container, and which by reason of its distinctive appearance and uniqueness at 65 once attracts the eye and indicates the contents of the container. For instance, if the container is filled with strawberry jam or jelly, the ornamental figure or character of the cover is a perfect representation of a 70 strawberry, in every respect made as true to nature as possible. The upstanding figure or character in every case is formed as a true representation of the fruit sealed within the container, so at a mere glance the 75 housewife or other may determine the contents of the container.

By the use of the described ornamental cover for the container, the necessity of attaching to the outside of the container written or printed labels to designate the contents thereof is eliminated, and which is a feature which will readily appeal to those required to put up fruit and jellies in large 85 quantities.

Preferably, the ornamental base 5 and the figure or character 6 associated therewith, 90 I form of molded material, the base 5 being cemented or otherwise securely held to the upper or exterior face of the cover 3, but the manner of forming these features is immaterial.

The cover is exceedingly neat and attractive in appearance, and by its baldness as to outline, configuration, and the color scheme, 95 presents a ready and quick means of identification as to the contents of the sealed container.

For the use of manufacturers and dealers generally placing preserves, fruits and 100 jellies on the market in sealed containers, the use of the present invention eliminates the use of expensive and highly decorative printed labels generally employed to designate the products of the sealed containers, 105 while permitting the products to be placed on the market not only in a unique and distinctive form of dress appearance, but equally so in a container by which the contents thereof is determined by visual inspection of its closure cap or cover.

I am well aware that the closure cover

with its associated ornamental figure or part thereof and representing the particular character may be formed in various ways and therefore do not wish to be understood as limiting or restricting the same to the manner described, but on the contrary wish to cover the invention as broadly as the state of the art will permit.

I claim:—

1. In combination with a jar, a removable cover for closing and sealing the mouth thereof, said cover mounting a molded character in bas relief forming an integral

2. A means for specifically identifying and labeling the contents of a container, comprising a closure for such container having as a part thereof a projecting portion simulating the original fruit, berry or the like from which the contents of the container is made.

In testimony whereof I have signed my name to this specification.

CORALIE SELBY OLNEY.
